CHARLES R. GREUTER, OF CHICAGO, ILLINOIS.

INTAKE HEATER.

Application filed March 7, 1925. Serial No. 13,879.

This invention relates to intake heaters for internal combustion engines and particularly to such heaters applied to engines of the valve-in-the-head type.

- 5 In order to secure the desired port areas with complete accessibility and attractive appearance it is desirable to place the intake manifold on one side of the cylinder block and the exhaust manifold on the opposite side. When this is done, it has heretofore been found difficult to employ the exhaust gases, or part of them, in an intake heater. In prior structures recourse was had to external piping, which did not give 15 the desired free flow of exhaust gases to the heater and which not only detracted from the appearance of the engine, but was in the way when repairs or adjustments were necessary.
- 20 The present invention avoids all these difficulties and secures a peculiarly efficient heater by surrounding a portion of the inlet manifold with a heating jacket and connecting the two ends of the heating jacket to 25 two corresponding ports, each port leading from the main exhaust port of a corresponding one of two cylinders. These branch ports thus extend across the cylinder head to the inlet side of the engine, and they may 30 conveniently be connected to the exhaust ports of two adjacent cylinders. The heating jacket and its connections to the branch ports may be cast integrally with the inlet manifold, thus producing a very neat and 35 simple structure devoid of piping.
- Since the two cylinders, whose exhaust ports are connected by the branch ports to the opposite ends of the heating jacket, do not exhaust simultaneously, a part of the 40 exhaust from each cylinder reaches the exhaust manifold through the exhaust port of the other cylinder, passing on the way through the branch ports and the heating jacket. The flow through the jacket is thus 45 alternating in direction, so that the heating effect throughout the length of the heating jacket is uniform. Moreover, the exhaust passage offered through the heating jacket may be made very free, so that any desired 50 portion of the exhaust gases from these two cylinders may be made to pass through the heating jacket in preference to passing directly through the main exhaust port to the exhaust manifold.
- 55 From the above it follows that not only

does the design lead to a simple, self-contained structure, but it permits a structure which may be so varied in its specific form as to give any desired heating effect. Connection of the heating jacket to two cylinders is sufficient, but obviously the principle of the invention might be extended by connecting the jacket in the same way to more than two cylinder exhaust ports.

The preferred embodiment of the invention is illustrated in the accompanying drawings as applied to a multi-cylinder engine in which each group of four cylinders is fed by a single carburetor, so that the inlet manifold supplies four cylinders. The valves 60 might be actuated in any suitable manner, but in the example illustrated they are actuated directly by cams on an overhead cam shaft. Obviously more than four cylinders 65 might be connected to a single manifold, if 70 desired.

In the drawings,

Fig. 1 is a fragmentary plan view partly in section, showing the cylinder head, the cam shaft, its bearings and housing being 80 removed.

Fig. 2 is a section on the line 2—2 of Fig. 1, but shows the cam shaft and its housing in place.

The cylinder head 6 is provided with the 85 usual combustion spaces 7 to each of which leads an inlet port 8 provided with an inlet valve 9 of the ordinary poppet type. The inlet valve stems are shown at 10 and are guided and actuated in the same manner as 90 the exhaust valves which will be hereinafter described.

The exhaust ports are shown at 11 and are controlled by poppet exhaust valves 12. Each valve is guided and actuated by means 95 of a stem 13 carrying at its upper end a head or tappet 14 whose exact construction is not material to the present invention. The tappet 14 is confined by a guide 15 which also serves to house the valve spring 16. Each 100 tappet 14 is engaged directly by a corresponding cam 17 on the cam shaft 18. This cam shaft turns in bearings not shown in detail in the drawing and not material to the present invention. The valve mechanism 105 will be recognized as conforming in its main features with known practice.

The exhaust manifold is shown at 19 and preferably is so arranged that a single manifold receives the exhaust from all the cyl- 110

inders of the engine through a series of exhaust branches 20 which connect with the various exhaust ports 11.

The inlet manifold 21, in the particular example illustrated, supplies four cylinders through the branch connections 22 which communicate with the inlet ports 8. The carburetor, not shown, attaches to the flange 23 and feeds the inlet manifold through the port 24. The middle portion of the manifold 21 is surrounded by a shell 25 which provides an annular jacket space 26. This communicates through the branch connections 27 with branch ports 28 which extend from the inlet side of the head to the main exhaust ports 11 of the middle two cylinders of the group fed by the inlet manifold. The shell 25, which encloses the jacket space 26, and the connections 27 are cast integrally with the inlet manifold, so a single unitary structure is provided. The threaded openings indicated at 29 are merely core holes and are plugged. A baffle or partition 30 is provided across the jacket space 26 at the side toward the cylinder for the purpose of ensuring the flow of exhaust gases on all sides of the inlet manifold. In Fig. 1 a spark plug is shown at 31 and a portion of the cylinder block at 32.

When the engine is running, the jacket space 26 will offer passage to exhaust gases flowing from one of the connected cylinders through the heater to the exhaust passage of the other connected cylinder. The baffle 30 forces the gases to flow on all sides of the exhaust manifold and since the flow is alternate in direction, the action of the heater is uniform throughout its length.

The structure is simple and inexpensive to construct, attractive in appearance, and since it avoids all extra connections, imposes no difficulties or extra labor in assembling and dismounting the engine. These facts, coupled with its marked efficiency, render it a peculiarly desirable construction.

What is claimed is:

1. The combination of a multicylinder internal combustion engine having its cylinders arranged in line, with inlet and exhaust ports terminating respectively in opposite sides of the row of cylinders, and having branch ports formed in the walls of the cylinder structure and leading from the exhaust ports of a plurality of cylinders to the inlet side of the engine; an inlet manifold connected to said engine and having branches leading to inlet ports; and a duct for exhaust gases connected exclusively to said branch ports and in heat exchanging relation with said inlet manifold.

2. The combination of a multicylinder internal combustion engine having its cylinders arranged in line, with inlet and exhaust ports terminating respectively in opposite sides of the row of cylinders and having two branch ports formed in the walls of the cylinder structure and leading separately from the exhaust ports of two cylinders to the inlet side of the engine; an inlet manifold connected with said inlet ports; and a heater duct connected exclusively with said branch ports, said duct being in heat conducting relation with said inlet manifold and connected with said branch ports at its ends.

3. The combination of a multicylinder internal combustion engine having its cylinders arranged in line, with inlet and exhaust ports terminating respectively in opposite sides of the row of cylinders, and having branch ports formed in the walls of the cylinder structure and leading from the exhaust ports of a plurality of cylinders to the inlet side of the engine; and a unitary inlet manifold connected with said engine and including a main supply passage with branches leading to inlet ports and a separate heater passage communicating exclusively with said branch ports.

4. The combination of a multicylinder internal combustion engine having its cylinders arranged in line, with inlet and exhaust valves mounted in the cylinder heads, inlet ports leading from one side of the row of cylinders to the inlet valves, exhaust ports leading to the other side of the row of cylinders from the exhaust valves, and branch ports extending from two exhaust ports to the inlet side of the row of cylinders; and a unitary inlet manifold connected with said engine and including a main supply passage with branches leading to inlet ports and a separate heater passage communicating exclusively with said branch ports.

5. The combination of a multicylinder internal combustion engine having its cylinders arranged in line, with inlet and exhaust valves mounted in the cylinder heads, inlet ports leading from one side of the row of cylinders to the inlet valves, exhaust ports leading to the other side of the row of cylinders from the exhaust valves, and branch ports extending from two exhaust ports to the inlet side of the row of cylinders; an inlet manifold; and a heater for said manifold connected exclusively with said branch ports.

In testimony whereof I have signed my name to this specification.

CHARLES R. GREUTER.
